TWIN-SCREW ARMORED CABLE CONNECTOR

Martin D. Bergan, Westfield, N. J., assignor to The Thomas & Betts Co., Elizabeth, N. J., a corporation of New Jersey

Application June 2, 1947, Serial No. 751,716

3 Claims. (Cl. 285—6.5)

1

The invention relates to electric connectors of the type designed to secure conductors such as BX cables to an outlet box.

It is known at present to provide a tubular form of outlet box connector which is secured to an opening in the outlet box in various ways, and in which a cable is intruded into a tubular portion and arranged to permit a cut back portion of the cable to engage a bushing or stop flange on the inner end of the tube and which tubular portion is provided in the accessible part of the connector exteriorly of the box with different forms of clamping devices for securing the cable thereto.

In general, the connectors of this type now on the market are designed to accommodate only a few sizes of conductors or cable with a limited range of maximum to minimum diameters.

There has recently appeared on the market a new type of BX cable of relatively small diameter. It is physically impossible to use the present forms of connector to secure both the usual size and the new small diametered conductor to the box.

The primary object of the invention is to provide a standard form of connector which can be used to receive and secure to the outlet box any diameter of cable within the scope of those which can be intruded into the bore of the tubular part of the connector including the larger types marketed for many years plus the small size recently added to the market.

Broadly this objective is obtained by utilizing two screws in transversely offset relation and operatively disposed to engage and secure in place in the connector conductors or cables of any diameter within the capacity of the tube bore.

It has been known heretofore to use a single screw, sometimes called a tangential screw, arranged to engage the intruded conductor or cable offset from the axis of the same in order to avoid crushing the usual metal shell on BX conductors as would happen if the screw engaged the shell or armor in line with its axis. The present disclosure contemplates the retention of this tangential engagement of the conductors or cables irrespective of their diameters.

It has been suggested in the case of the single screw clamping arrangement to provide a screw of sufficiently large diameter to contact the small size contained cable irrespective of its diameter. It has been found, however, that this suggested arrangement is too expensive and the dual screw assembly herein featured is found to be cheaper to manufacture than any such abnormally size

2

screws. The present invention features in the case of the small diametered cable, the use of one of the screws not as a clamping device, but as a shifting or locating device for laterally shifting the small diametered cable into position to be engaged by the other screw functioning as a clamp and preferably to have the other screw engage the cable in the preferred form of off centered contact.

10 Various other objects and advantages of the invention will be in part obvious from an inspection of the accompanying drawings and in part will be more fully set forth in the following particular description of two forms of dual screw clamp embodying the invention, and the invention also consists in certain new and novel features of construction and combination of parts hereinafter set forth and claimed.

15 In the accompanying drawings: Figure 1 is a view in axially vertical section of a connector constituting a preferred embodiment of the invention operatively securing a conductor of relatively small diameter to an outlet box; and taken on the broken line 1—1 of Fig. 4;

20 Figure 2 is an end view of the showing of Figure 1 as viewed with a relatively large diametered cable substituted for the smaller cable therein shown, and with one of the screws removed from the connector, and in general showing a known structure;

25 Figures 3 and 4 are views in end elevation taken on the plane indicated by the line 4—4 of Figure 1 looking in the direction of the arrow and showing the small diametered cable in transverse cross section; Figure 3 showing the first step in the manner herein featured of shifting the conductor cable laterally before it is locked in the connector; and Figure 4 showing the parts in their final locked position and which locked position is also shown in Figure 1;

30 Figure 5 is another view corresponding insofar as the connector is shown to Figures 3 and 4, showing both screws advanced into a dual clamping engagement with a cable of intermediate size;

35 Figure 6 is a horizontal sectional view taken on the line 6—6 of Figure 1, looking downwardly and showing the two screws in dotted outline with their intruded ends engaged in a trough between two adjacent turns of the spiral corrugation of the cable and;

40 Figure 7 is a view in vertical longitudinal section of the connector shown in the preceding figures taken axially through either screw and 55 with slightly modified form of screw substituted

for either or both of the screws of the preceding figures.

In the drawings and referring first to the Fig. 1 showing there is disclosed an outlet box A provided with a hole B in the side thereof and into which hole is intruded a connector 10 particularly forming the subject matter of this disclosure. The connector is of somewhat conventional form and includes a tubular member 11 having a bore 12, the inner end of which is partially closed by a bushing 13 forming a stop for limiting the intrusion of any size cable generally designated as C into the tubular member. The member 11 is provided in spaced relation to both of its ends with an outstanding corrugation 14 which forms an abutment for engaging against the outer side of the box and thus acting as an abutment to limit the intrusion of the connector into the box. The portion of the connector which is intruded into the hole B forms an extension 15 exteriorly threaded as at 16 and which is engaged by a nut 17 to clamp the wall of the box between the corrugation 14 and nut 17. The outwardly extending portion 18 of the connector has a cross-sectional configuration, as shown in Figures 2 to 5, which includes a curved substantially semi-cylindrical bottom side or seat 19 and a relatively flat upper side 20. The seat 19 and the flat top side are integrally connected at opposite sides by upstanding parallel sides 21--22, to coact therewith to form a ring-like band. The structure as thus far described is somewhat of conventional design.

The particular feature of this disclosure is that two ordinary machine screws 23 and 24 are threaded through the flat upper side 20 in transversely spaced apart parallel relation, designed in the case of the larger size conductor as shown in Figure 2 to have either screw engage a large size conductor LC on either side of its axis D. In the case where the larger size conductor is used, either screw, such for instance as the left screw 23, may be entirely omitted and under these circumstances the device resembles known structure except, of course, for the presence of the screw hole for receiving the screw 23.

Assuming a small size conductor or cable SC is inserted into the tubular member as indicated in Figures 1, 3 and 4, the right screw 24 is advanced preferably to the limit of its movement as shown in Figure 3 engaging the cable SC tangentially and with its intruded end engaging or almost engaging the curved side or seat 19. In this case the right screw 24 extends into the bore 12 for a distance more than one-half that between the flat side 20 and the curved bottom side 19. This has the effect of pushing the conductor SC laterally towards the left so that the conductor SC is squeezed between the side of the screw 24 and the left side of the curved seat portion, and substantially in the line of thrust of the left or binding screw 23. With a small diameter conductor so located in place and fixed against shifting transversely, the left screw is advanced inwardly and thus into binding engagement with the conductor SC as shown in Figure 4. It is thus seen that the right screw is not functioning in this case as a binding screw but as a means for reducing the horizontally cross section of the bore 12. While these two extreme positions have been indicated and illustrated respectively in Figures 2 and 4, it is obviously within the scope of the disclosure to secure in place conductors or cables whose diameters fall between these two extremes. For instance, in the event a conductor of intermediate size is used as shown in Figure 5, both screws may

be advanced more or less equally and thus used as dual clamping screws.

In the showing in Figures 5 the screws 25 and 26 are of equal length, more nearly of the size of the shorter screw 23 and engage the intermediate size cable IC on opposite sides of its crown and thus to locate their lines of thrust offset from the axis of the cable IC. In this case, the underside of the cable IC fits more or less snugly on the seat 19 and substantially centered in the connector. In this way, the two screws 25 and 26 can be advanced equally to distribute pressure more or less equally on the intermediate size cables or even on the large size cable LC of Fig. 2, or one screw can be advanced beyond the other if such permissible unbalancing or pressure becomes feasible for any reason.

The arrangement of the screws as thus far described consider their axes as located more or less accurately in the same transverse plane. As suggested in Figure 6, the screws may be relatively off-set slightly axially of the bore or otherwise so spaced that their intruded ends will bear in the troughs E formed between the corrugations F of the cable armor G.

In the preceding figures, the screws have been shown to be of the usual type of flat ended machine screws. Of course, such screws are extremely cheap and this is a controlling reason for their use. It is suggested, however, as shown in Figure 7 that the intruded ends of the screws 27 be tapered to show fingers 28 of frusto-conical design and dimensioned to fit between adjacent sides H and I of the corrugations F as they turn or round inwardly from their crown J to form the troughs E. This structure has the additional advantage of forcing the conductor or cable C irrespective of its or their diameters from right to left of the showing in Figure 1 as indicated by the arrow in Figure 7 so as to force its end bushing K into firm engagement with its stop or bushing flange 13.

In this way the connector 10 may be supplied as a standard size unit and simply by substituting the necessary size and type of screw, which the operator can carry with him in stock, the connector may be conveniently set up to receive the particular size of cable indicated for the instant job.

50 I claim:

1. A sheet metal connector for securing a cable to a box having an opening in a side thereof, said connector including a tubular member with one end threaded and forming an extension for insertion into the box opening, said tubular member provided exteriorly with a corrugation adjacent its midlength to form a stop for engaging one side of the box and thus to limit the intrusion of the connector into the box, said member provided at its inner end with an inwardly bent portion forming a bushing for limiting the intrusion of the cable into the member, the other end of the tubular member when considered in cross section having a flat top side, a curved bottom side forming a seat for the cable and parallel side walls connecting the bottom and sides and a pair of screws spaced apart transversely of the axis of the bore on opposite sides thereof spaced apart axially and threaded through the flat top side closely adjacent the corrugation for engaging the conductor for the time being in the bore of the tubular part, at least one of said screws having a length to extend more than half way from the flat to the curved side to fill up approximately the space in one-half of the bore cross section leav-

ing the balance of the bore cross section open to receive a cable therein positioned to be engaged by the other screw.

2. In a device of the class described, the combination of a tubular metallic connector provided with a bore for receiving cables of different diameters, a cable within the bore having materially less cross section than the cross section of the bore, thus leaving a space in the bore not occupied by the cable, a pair of screws threaded through the side of the connector and disposed in relative transverse relation, the portions of the screws within the bore forming fillers tending to occupy the space considered transversely not occupied by the cable and at least one of the screws having its free end within the bore bearing on the cable and acting along a thrust line offset from the axis of the cable thereby to clamp it at three points, that is, at the advance end of said screw, at the portion of the connector opposite the screw, and at the other screw.

3. A connector including a tubular part pro-

vided with means for securing it to an outlet box and into the bore of which connector cables of different diameters may be intruded, a pair of screws in spaced apart relation threaded through the same side of the member for engaging the cable contained therein, at least one of the screws when advanced acting to reduce the available space within the outline projected of the other screw and into which restricted space a cable of small diameter may be introduced in position to be clamped by said other screw.
